[57] CLAIM

The ornamental design for a combined truck cab body exterior and front bumper, as shown and described.

DESCRIPTION

FIG. 1 is a front perspective view of a combined truck cab body exterior and front bumper constructed in accordance to the teachings of the present design, it being understood that the roof is plain and unornamented and that the broken line showing throughout the figures is merely illustrative and forms no part of the present design;

FIG. 2 is a rear perspective view of the combined truck cab body exterior and front bumper shown in FIG. 1; FIG. 3 is a side view of the combined truck cab body exterior and front bumper shown in FIG. 1, the side opposite to that shown being a mirror image thereof; and,

FIG. 4 is an enlarged front view of the combined truck cab body exterior and front bumper shown in FIG. 1.
